UNITED STATES PATENT OFFICE

2,489,570

PLATE SETTING FOR CAP JEWELS

Henri Gerber, Bienne, Switzerland, assignor to
Omega Louis Brandt & Frere S. A., a joint-stock
company

Application October 8, 1946, Serial No. 702,001
In Switzerland October 11, 1945

4 Claims. (Cl. 58—140)

1

This invention relates to plate settings for cap jewels. In small size watches it is often necessary to provide a plate-setting of oblong shape for the cap jewel, that can be secured at one end by means of a screw, the cap jewel being set in the other end.

This construction has the disadvantage that the said plate-setting does not always lie perfectly flat on the surface provided as a seat with the result that the face of the cap jewel comes to lie at an angle to the axis of the balance, thus giving rise to defective working of the pivot of the verge, not to mention the fact that the oil will not easily remain on the pivot.

The aim of my invention is to remedy these inconveniences. Thus, an object of my invention is to ensure perfect seating of the said plate. Another object is to reduce the space taken up by this plate to a minimum. I obtain these aims by providing the feature that the contour of the rounded head portion forming the setting is bevelled, and that the tail end, likewise provided with bevelled surfaces, opens in the shape of a V, the head portion fitting into a bevelled undercut recess formed in the plate covering the balance and the V shaped tail end being held against the said plate by means of a screw with inverted cone head, so that on tightening the screw the plate-setting will be wedged into its proper place, and consequently the cap jewel will lie flat in place.

The attached drawing shows, by way of example, an embodiment of the plate-setting according to the present invention.

Fig. 1 is a longitudinal section along the line I—I in Fig. 2, through the axes of the cap jewel and the wedge screw.

Fig. 2 is a plan view.

The plate 1 is milled so as to form a seat for the plate-setting. A hole 3 is drilled in one end of this seat to receive the balance jewel, not represented, and near the other end, an internal thread 4 is made to take the wedge screw 5 with inverted cone head. The wall of the recess forming the seat spreads outward toward the bottom. The head portion 6 of the plate setting has corresponding but, with respect to the bottom surface of the recess, more obtusely bevelled contour and fits into the said recess. A hole having the same axis as the balance staff is drilled in the plate-setting, in which the cap jewel 8 is set. The semi-circular contour of the head portion forming the setting is continued by two rectilinear segments 9; at the other end, i. e. at the opposite end with respect to the hole for the cap jewel, the plate-setting opens in the shape of a V, 10, with

2

rounded base, its inner edges being obtusely bevelled.

The screw 5 tightens on the bevelled edge of the V-shaped portion 10, pushing the plate-setting 2 longitudinally toward the bevelled end of the recess. In this manner, the plate-setting is pressed down, under the action of compounded forces, on to its seat, and the cap jewel is consequently held flat in position.

The sides 11 of the plate-setting 2 can be made curved to receive the jaws of pick pincers used to take hold of it when in the recess.

What I claim is:

1. In a watch movement, a plate having an undercut recess, a cap jewel, a plate setting comprising a rounded hollow head portion having a bevelled contour and receiving said cap jewel and fitting by its bevelled contour into said undercut recess, said plate setting further comprising a tail portion at the opposite end with a V-shaped opening provided with a bevelled inner edge, and a screw with a head in contact with said bevelled inner edge to force said plate-setting flat against the bottom of said undercut recess.

2. In a watch movement, a plate having a bevelled undercut recess, a plate setting comprising a rounded head portion having a semi-circular bevelled contour and a hole concentric with said contour, a cap jewel set into said hole, said plate setting fitting by its bevelled contour into said bevelled undercut recess and comprising at the end opposite to said head portion a tail portion with a V-shaped opening provided with a bevelled inner edge, and a screw screwed into said plate

30 and provided with an inverted cone head in contact with said bevelled inner edge to force said plate-setting flat against the bottom of said bevelled undercut recess.

3. In a watch movement, a plate having a bevelled undercut recess, an oblong plate setting comprising a rounded head portion having a semi-circular bevelled contour and a hole concentric with said contour, a cap jewel set into said hole, said plate setting fitting by its bevelled contour into said bevelled undercut recess and comprising a tail portion with a V-shaped opening provided with a bevelled inner edge, two rectilinear segments continuing said semi-circular contour, and curved portions connecting said rectilinear segments and said tail portion to permit

45 pick pincers to take hold of said plate setting, and a screw screwed into said plate and provided with an inverted cone head in contact with said bevelled inner edge to force said plate-setting flat

against the bottom of said bevelled undercut recess.

4. In a watch movement, a plate having an undercut recess, a cap jewel, a plate setting comprising a hollow head portion receiving said cap jewel and fitting by its contour into said undercut recess in such a manner that on a lateral adjusting of said plate-setting the contour of said head portion is displaced along the contour of said undercut recess towards the bottom of said recess, said plate setting further comprising a tail portion at the opposite end with a notch provided with a bevelled inner edge, and a screw with a head in contact with said bevelled inner edge to

force said plate-setting flat against the bottom of said undercut recess by lateral and axial pressure of said screw onto said plate setting.

HENRI GERBER.
